Application May 15, 1942, Serial No. 443,117

13 Claims. (Cl. 250—27)

1

The present invention relates to electronic switches and, particularly, to such switches of the multiunit or multistage type used selectively to couple one or more signal sources to one or more output circuits.

It is often desirable to provide an electronic switch by which any selected one of a plurality of signals may be coupled to a translating circuit, or to translating circuits individual to such signals, or in which one signal may be selectively coupled to any one of a plurality of translating circuits. While mechanical switches have been used for this purpose, an electronic switch has numerous advantages in many applications. Outstanding among these advantages are its substantially instantaneous operation, the fact that it is controllable by a potential alone and thus requires no appreciable consumption of power in its control circuit, its stable and positive action, and its freedom from the many troubles which characterize the use of electrical contacts necessarily used in mechanical switches.

It is frequently desirable that a multistage electronic switch be provided with one control circuit by which selectively to control the several switching stages thereof. Where the electronic switch has a single control circuit for all stages, it is desirable that each switching stage be positively, stably, and selectively controlled by individual values of a characteristic of a control signal or potential applied to the control circuit. In order that the switch may be suitable for a wide variety of applications, it is desirable that the values of the control potential or signal which selectively control the switching stages thereof may occur in any desired order or may even occur in a random order as the circumstances of the particular application demand. It is further desirable that an electronic switch shall involve a minimum of circuit elements and apparatus, that it shall have a simple circuit arrangement, shall be inexpensive and adaptable to many and diverse applications, and that it shall be characterized by stable and reliable operation over long periods of use.

It is an object of the present invention, therefore, to provide a new and improved electronic switch of the type described.

It is a further object of the invention to provide a new and improved electronic switch which possesses one or more of the desirable features heretofore specified.

It is an additional object of the invention to provide an electronic switch of the multistage type wherein the stages thereof may be selective-

2

ly controlled by individual amplitude values of a control potential and one wherein such values of the control potential may occur in any random order as desired.

5 In accordance with the invention, an electronic switch comprises a plurality of vacuum-tube switching stages each including an output circuit at which a signal translated by the stage is developed. The conductance characteristics of 10 the stages depend primarily on the values of space currents of the aforesaid vacuum tubes. The electronic switch includes a signal input circuit for each of the stages, and means for applying to each of the stages a signal input having 15 an effective amplitude varying over a predetermined amplitude range, at least a portion of each of the signal input circuits being common to all of the stages. There is additionally included in the electronic switch means individual to the 20 stages for controlling the conductance characteristic of each stage thereof to render each of the stages responsive to individual portions of the amplitude range of the signal input, selectively to translate the portion of the signal input lying 25 within the aforesaid portions of the amplitude range, the last-mentioned means in at least one of the stages including means for rendering the one stage unresponsive to all amplitude values of the input signal different from the aforesaid portion of the aforesaid amplitude range individual to the one of the stages.

30 In accordance with a particular form of the invention, an electronic switch comprises a plurality of vacuum-tube switching stages each including an input circuit having a circuit portion 35 adapted to have applied thereto a signal and each including an output circuit at which the signal is developed after translation through the aforesaid each stage. The conductance characteristics of 40 the stages depend primarily on the values of space currents of the vacuum tubes thereof. Another portion of the input circuits of the stages is common to all of the stages and is adapted to have applied thereto a control potential having 45 selectively-variable amplitude values. The switch includes means individual to the stages for controlling the conductance characteristics thereof to render each of the stages responsive to at least individual amplitude values of the control potential, selectively to translate the applied signals from the input circuit to the output circuit associated therewith, the last-mentioned means in at least one of the stages including means for rendering the one of the stages unresponsive to 50 all amplitude values of the control potential dif-

ferent from the aforesaid amplitude value individual to the one of the stages.

For a better understanding of the present invention, together with other and further objects thereof, reference is had to the following description taken in connection with the accompanying drawings, and its scope will be pointed out in the appended claims.

Referring now to the drawings, Fig. 1 is a circuit diagram, partly schematic, of a complete electronic switch embodying the invention; Figs. 2, 3, and 4 are graphs used as an aid in explaining the operation of the invention; and Figs. 5 and 6 are circuit diagrams of electronic switches embodying modified forms of the invention.

Referring more particularly to Fig. 1 of the drawings, there is represented a complete electronic switch embodying the present invention in an arrangement having numerous applications as will hereinafter be pointed out in greater detail. This electronic switch comprises several units; namely, an electronic switch unit per se, designated by the reference numeral 10, a step-voltage generating unit 11, and a periodic-pulse generating unit 12. Briefly considered, it is the purpose of the unit 12 to generate a periodic potential of pulse wave form which is applied to an input circuit of the generator 11. The latter derives from this periodic potential another periodic potential the amplitude values of which increase by successive steps during each period thereof. This step voltage is applied to a control circuit of the electronic-switching unit 10 to cause the switching stages thereof to be successively and periodically controlled, thereby successively to translate a plurality of signals, individually applied to the switching stages of this unit, to individual ones of a plurality of output circuits of the electronic switch.

Considering first the detailed circuit arrangement of the electronic switch 10, this unit comprises a plurality of vacuum-tube switching stages 13-17, inclusive, only the detailed circuit arrangement of the stages 13 and 14 being shown for purposes of simplicity, it being understood that all of the stages 13-17, inclusive, are similar and include similar circuit elements in a similar circuit arrangement. Each such switching stage includes a vacuum tube 18 having a control electrode 19, a screen electrode 20, and an anode 21. Each stage also includes an input circuit coupled to the control electrode 19. This input circuit has a circuit portion, comprising the input or control-voltage circuit terminals 22, 23 of the electronic switch 10, common to all of the switching stages and has another circuit portion individual to each of the switching stages and adapted to have a signal applied thereto. Such individual circuit portion of the input circuit comprises the cathode circuit of vacuum tube 18 and includes a winding 24 and a source of operating bias comprising a battery 25 connected in series between the cathode of vacuum tube 18 and ground. There is coupled to the winding 24 a winding 26 which is connected to the input circuit terminals 22, 23 adapted to have applied thereto a signal which is to be translated through the switching stage associated therewith. Each of the switching stages also includes an output circuit comprising output circuit terminals 28, 29 to which the signal individual to each stage is applied after translation through each such stage.

The input or control circuit terminals 22, 23 of the electronic switch 10 are adapted to have applied thereto a control potential having selec-

tively-variable amplitude values. The electronic switch includes means individual to the switching stages thereof for controlling the conductance characteristic of each such stage to render each of the stages responsive only to at least individual amplitude values of the control potential, selectively to translate the applied signals from the input circuit to the output circuit associated therewith. This means comprises a load impedance or load resistor 31 of relatively high value, for example of the order of one-half to one meg-ohm, included in the output circuit of the vacuum tube 18 between the anode 21 thereof and a source of space current indicated as +B. The last-named means also comprises a source of operating bias indicated as +Sc for the screen electrode 20 of vacuum tube 18, the relative value of the operating potential of screen electrode 20 being critically proportioned in a manner presently to be explained, and effectively includes the battery 25 in the cathode circuit of the vacuum tube 18, the voltage of this battery also having a critical value as will presently be apparent. In the event that it is desirable in some application to use the unit 10 alone, provision must be made for completing a direct current path from the control electrode 19 to ground. This path normally will be completed through the external control circuit which is connected to the control circuit terminals 22, 23, as in the arrangement of Fig. 1. However, where this is not the case, a resistor R, indicated in broken lines for the reason that it may be comprised in whole or in part by the resistance of the external control circuit, is connected across the control circuit terminals 22, 23.

The periodic-pulse generator 12 is of the conventional blocking-oscillator type and includes a vacuum tube 32 and a transformer 33 having a primary winding 34 included in the output circuit of the vacuum tube 32, and a secondary winding 35 included in the input circuit of this vacuum tube. The input circuit of tube 32 additionally includes a grid resistor 36, a grid condenser 37, and a resistor 38, the latter being connected in series with the transformer winding 35 and being coupled to a synchronizing-signal input circuit comprising terminals 39, 40. A cathode resistor 41 is included in the output circuit of vacuum tube 32 and a periodic potential of pulse wave form developed across this resistor is applied through the output circuit terminals 42, 43 to the input circuit terminals 44, 45, respectively, of the step-voltage generating unit 11. Unit 12 in the Fig. 1 arrangement may be used for several purposes; for example, to provide a periodic potential of pulse wave form which is necessary to derive the step potential generated by the unit 11 or, when the Fig. 1 arrangement is used as a counter system by which to count the number 60 of pulses in a synchronizing signal applied to its input circuit terminals 39, 40 of unit 12, this unit may be used as a frequency divider wherein the frequency of the periodic potential generated by unit 12 will be a selected sub-multiple of the frequency of the periodic potential applied to its input circuit terminals 39, 40.

The step-voltage generator 11 includes a vacuum-tube repeater 46 having input electrodes coupled to the input circuit terminals 44, 45 of this unit and output electrodes coupled to a pair of rectifier devices 47, 48 which are connected in parallel with each other with opposite polarities. There is included in circuit with the rectifier device 48 a condenser 49 across which the step voltage is derived. A second vacuum-tube re-

peater 50 has its input electrodes coupled across the condenser 49 and includes an output circuit comprising a cathode resistor 51 which is coupled to the output circuit terminals 52, 53 of unit 11. In the operation of unit 11, it is necessary periodically to discharge the condenser 49 to reduce its voltage substantially to zero. There is provided in unit 11 for this purpose a transformer 54 having a winding 55 coupled across cathode resistor 51 and a secondary winding 56 which is coupled to the input electrodes of a vacuum tube 57. The control electrode of vacuum tube 57 is negatively biased from a source of potential 58. The anode and cathode elements of vacuum tube 57 are connected directly across the condenser 49.

In considering the operation of the Fig. 1 arrangement, the operation of the electronic switch unit 10 will first be considered and reference will be made to the curves of Figs. 2 and 3 for that purpose. Considering specifically the operation of one of the switching stages, for example the stage 13, it has been found that when the operating bias applied to the screen electrode 20 of the vacuum tube 18 is maintained constant at a given value, the use of a large value of resistance for the load resistor 31 has the effect that, over a wide range of control potentials applied from the control circuit terminals 22, 23 to the control electrode 19 of tube 18, the anode current of this tube starts from anode current cutoff, determined by the value of voltage of battery 25, and increases rapidly to a value at which no further increase is experienced. This anode current characteristic is represented by curve A of Fig. 2. Anode current cutoff occurs when the control potential has any value less than e_1 , lesser values of potential being insufficient to overcome the bias of battery 25, and the anode current has a large constant value when the control potential has any value larger than e_2 . The fact that the anode current of tube 18 becomes constant for any value of the control potential larger than the value e_2 is due to two factors. The first of these relates to the large voltage drop which the anode current produces across the load resistor 31 by virtue of the large value of resistance of the latter with the result that little or no voltage is applied to the anode 21 of tube 18 when the anode current becomes large. The second factor relates to the fact that the screen electrode has applied thereto a positive potential having a relatively high and constant value with the result that as the anode potential decreases due to increasing magnitudes of the potential drop across the resistor 31, the screen electrode tends to collect larger quantities of the electrons emitted by the cathode of tube 18 and ultimately collects completely any additional electrons emitted by the cathode. The particular value e_2 of the control potential which causes the anode current to become constant is thus determined both by the value of the load resistor 31 and by the value of the potential applied to the screen electrode 20.

It will be seen from curve A that the anode current of the vacuum tube 18 changes over the range e_1 – e_2 of the control potential, that is, to individual amplitude values thereof, but that the anode current has a relatively constant value for amplitude values of the control potential above this range and a substantially zero value for amplitude values below such range. Bearing in mind that the anode potential of tube 18 decreases with increasing values of its anode current due to the load resistor 31, the slope of

curve A at any given point cannot be used to give the exact value of transconductance of tube 18 at that point but is useful as an indication or measure of the transconductance. The broken-line curve B of Fig. 2 represents the manner in which the transconductance of the vacuum tube 18 varies with the control potential. It will be seen from curve B that the vacuum tube 18 has relatively high transconductance, and thus has a relatively high repeating ratio, at substantially one individual amplitude value e_3 of the control potential and has relatively low transconductance for amplitude values substantially different therefrom.

The value of control potential at which the vacuum tube 18 has high transconductance may be varied over a wide range by proportioning the values of the biasing battery 25, the value of the operating bias applied to the screen electrode 20, and the value of resistance of the load resistor 31. In practice, these values are so proportioned that each of the switching stages 13–17, inclusive, has high transconductance only at one individual amplitude value of the control potential, as represented by the curves of Fig. 3, wherein the curves A₁, A₂, A₃, A₄, A₅ represent the transconductance characteristic of the respective switching stages 13–17, inclusive. Only the switching stage 13 is thus responsive to the zero amplitude value of the control potential and is effective for this value of the control potential to translate the signal applied to its input circuit terminals 27, 28 to its output circuit terminals 29, 30. When the control potential has the amplitude value e_4 , the switching stage 13 is no longer responsive to the control potential, and hence the signal individually applied thereto is not translated to its output circuit terminals 29, 30. On the other hand, the switching stage 14 is responsive to this value of the control potential and is effective to translate the signal applied to its input circuit terminals 27, 28 to its output circuit terminals 29, 30. In similar manner, the switching stages 15, 16 and 17 are responsive to individual amplitude values e_5 , e_6 and e_7 , respectively, of the control potential selectively to translate the signals individually applied thereto from the input circuit to the output circuit associated therewith.

It will be evident that the individual amplitude values of the control potential at which the switching stages 13–17, inclusive, are responsive may occur in any random order. For example, if the control potential during a given interval has the successive amplitude values 0, e_7 , e_5 , e_6 , e_4 , the switching stages are rendered responsive in the corresponding order 13, 17, 15, 16 and 14. However, in the particular arrangement shown in Fig. 1, the switching stages 13–17, inclusive, are adapted to be rendered successively operative by a control potential applied to the control circuit terminals 22, 23 of unit 10, from the unit 11, having amplitude values which increase by successive steps. The manner in which this step voltage is produced will now be considered.

Consider first the operation of the periodic-potential generator 12. In the absence of a potential applied to its synchronizing circuit terminals 39, 40, a periodic potential of pulse wave form, represented by curve C of Fig. 4, is developed across the cathode resistor 41 by a blocking-oscillator action well understood in the art. This operation, briefly, is as follows: Starting at the time when the anode current of vacuum tube 32 just begins to increase, a voltage is induced in the winding 35 of the transformer 33 which drives the

grid of vacuum tube 32 in a positive direction. The anode current thereupon increases yet further with the result that a corresponding increase occurs in the positive potential applied to the control electrode. This action is cumulative until the anode current of vacuum tube 32 reaches a saturation value.

During the time when the anode current is thus increasing, the condenser 37 is charged by grid rectification. When the anode current of tube 32 reaches a constant value, a voltage is no longer induced in the winding 35 of the transformer 33 and the charge of the condenser 37 is effective to place a large negative bias upon the control electrode of tube 32, whereby the latter is biased to anode current cutoff. This action occurs very quickly since decreasing values of anode current induce a voltage in the winding 35 which drives the control electrode of tube 32 to an even higher negative potential. After a time interval, depending upon the time constant of condenser 37 and resistor 36, the charge leaks off of the condenser 37, anode current again begins to flow in the vacuum tube 32, and the cycle previously described is repeated.

The anode current of tube 32 flows through the cathode resistor 41 to develop thereacross the desired periodic potential. The period of this periodic potential is thus determined by the time constant of the condenser 37 and resistor 36 and may be made slightly longer than the period of a synchronizing signal applied to the input circuit terminals 39, 40, in order that the synchronizing signal may control in conventional manner the period of this potential, or may be made a multiple number of periods of the synchronizing signal, as desired. The periodic potential developed across the cathode resistor 41 is applied through the output circuit terminals 42, 43 to the input circuit terminals 44, 45 of the step-voltage generator 11.

The periodic potential pulses applied to the input circuit terminals 44, 45 of unit 11 are repeated by the vacuum-tube repeater 46 thereof and are applied to the rectifier devices 47 and 48. The rectifier device 48 conducts during the positive portions of the periodic potential applied thereto to charge the condenser 49 by a finite value to produce for each pulse of the periodic potential one step of the desired step potential. The rectifier device 47 conducts during the negative portion of the applied periodic potential to preserve at the rectifier devices 47 and 48 the electrical axis of the periodic potential.

The wave form of the desired step potential is represented by the curve D of Fig. 4 and it will be seen that the amplitude values of this voltage successively increase through a desired number of steps, for example five. At the end of the last such step, the potential across the condenser 49 must be reduced to zero. This is effected by the discharge vacuum tube 57 in the following manner. The potential developed across the condenser 49 is repeated by the vacuum tube 50 to the cathode resistor 51 thereof and is also applied between the anode and cathode of the discharge vacuum tube 57. Increases in value of the step potential developed across the cathode resistor 51 of tube 50 are applied as small negative pulses through the transformer 54 to the control electrode of the vacuum tube 57, but have no effect since the latter is biased by the battery 58 to a value such that tube 57 becomes conductive only when its anode potential, developed across the condenser 49, becomes

slightly larger than the value of the last desired step of the step potential. Tube 57 upon becoming conductive starts to discharge the condenser 49 which, of course, reduces the potential developed across cathode resistor 51 of tube 50 and causes a positive pulse to be applied through the transformer 54 to the control electrode of tube 57, thus tending to increase the anode current of tube 57 even more. This action is cumulative to drive the control electrode of tube 57 so far positive that this tube has a very low value of conductance, thus causing tube 57 substantially instantly and completely to discharge the condenser 49. When this has occurred, the voltage developed across the cathode resistor 51 of tube 50 assumes a steady-state value and no voltage is thereafter applied through the transformer 54 to the control electrode of vacuum tube 57. The latter thereupon again becomes nonconductive due to the bias applied to its control electrode from battery 58, and the cycle is repeated.

The step potential thus developed across cathode resistor 51 of vacuum tube 50 is applied through the output circuit terminals 52, 53 of unit 11 to the input circuit or control circuit terminals 22, 23 of unit 10 to cause the switching stages 13-17, inclusive, thereof to become successively operative in the manner previously described.

While the units 10, 11, and 12 are shown in Fig. 1 as being interconnected, it will be evident that the switching unit 10 may be used alone, in which event a suitable control potential having selectively-variable amplitude values is applied to its control circuit terminals 22, 23 selectively to render the switching stages 13-17, inclusive, operative in the manner described. On the other hand, the units 10 and 11 may alone be used together as a counter system for counting the number of pulses, for example, of a periodic-pulse potential applied to the input circuit terminals 44, 45 of the unit 11. The units 10, 11 and 12 have a useful application as a counter system for measuring the number of pulses of a periodic-pulse potential applied to the input circuit terminals 39, 40 of unit 12 and, when so used, the number of pulses indicated by the system may be the exact number of pulses of the applied potential or a sub-multiple number thereof, as desired.

The foregoing description of the switching unit 10 may seem to indicate that the switching stages 13-17, inclusive, thereof can only be responsive to such widely-spaced individual amplitude values of the control potential applied to the control circuit terminals 22, 23 that there are values of the control potential at which all of the switching stages have substantially zero transconductance. However, this is not the case, for it will be evident that the circuit constants of the switching stages may be so adjusted and proportioned, if desired, that two or more of the switching stages have maximum response to the same given amplitude value of the control potential or, alternatively, two of the stages may have overlapping transconductance characteristics. Where two such stages have overlapping transconductance characteristics as last suggested, each will have maximum response to an individual amplitude value of the control potential, but both may have some partial response at intermediate values of the control potential. The latter arrangement may have a useful application, for example, in television systems where it

is desired gradually to fade from one television picture signal to another.

From the above description of the unit 10 of Fig. 1, it will be evident that the biasing battery 25, the space current source +B together with the resistor 31, and the source +Sc of operating bias for the screen electrode 28 of the vacuum tube 18, comprise means for individually fixedly biasing each of the stages 13-17, inclusive, of the electronic switch 10 to control a conductance characteristic thereof to render each of the stages only responsive to at least individual amplitude values of the control potential selectively to translate the applied signals from the input circuit to the output circuit associated therewith. That is, these elements comprise means individual to the switching stages 13-17, inclusive, for imparting to each of the stages a relatively high transconductance when the control potential has at least individual amplitude values and a relatively low transconductance for other amplitude values thereof to render each of the stages only responsive to individual amplitude values of the control potential.

Fig. 5 represents a circuit diagram of an electronic switch embodying a modified form of the invention which is essentially similar to the electronic switch 10 of Fig. 1, similar circuit elements being designated by similar reference numerals and analogous circuit elements by similar reference numerals primed. While only three switching stages 13', 14', and 15' are here shown, it will be evident that other similar stages may be used if desired, as in the Fig. 1 arrangement. The present arrangement permits the use of the triode type of vacuum tube 18' although this type of tube is not essential to the operation of the instant arrangement and a screen-grid type of tube may be used, if desired, as in the Fig. 1 arrangement, there being the difference where the latter type of tube is used that the screen-grid potential has a normal value and the load resistor 31 a normal value of resistance; that is, these circuit parameters need not be specially proportioned as in the Fig. 1 arrangement. The principal distinguishing feature between the Fig. 1 and Fig. 5 arrangements consists in the use of two resistors 60, 61 which are connected in series between the control electrode 19 of the vacuum tube 18' and one control circuit terminal, for example the terminal 22, of the electronic switch 10'. The winding 24 of the input transformer 24, 26 of each of the switching stages is coupled through a condenser 62 to the common junction of the resistors 60 and 61.

Considering now the operation of the Fig. 5 arrangement, the switching stages 13', 14', and 15' are initially adjusted for operation by choosing a value of potential of the bias battery 25 of each such that the vacuum tube 18' of each switching stage is normally biased on the linear portion of its operating characteristic at one individual amplitude value of the control potential applied to the control circuit terminals 22, 23. Assume, for example, that the value of the control potential at a given time is such that the algebraic sum of its value and that of the battery 25 of stage 13' is correct to operate the vacuum tube 18' of this stage on the linear portions of its operating characteristic. This vacuum tube is thus effective at this time to translate the signal applied to its input circuit terminals 27, 28 to its output circuit terminals 29, 30. At the same time, however, this amplitude value of the applied control potential is insuffi-

cient to cause the vacuum tubes of the switches 14' and 15' to be biased above anode current cutoff and hence the latter stages are not effective to translate the signals applied thereto to their respective output circuits.

Now assume that the amplitude of the applied control potential increases so that the algebraic sum of its value and that of the battery 25 of the switching stage 14' is correct to bias the vacuum tube 18' of the switching stage 14' to the linear portion of its characteristic. The switching stage 14' thereupon becomes effective to translate the signal applied to its input circuit terminals 27, 28 to its output circuit terminals 29, 30. This value of control potential is as yet insufficient to bias the vacuum tube of the switching stage 15' above anode current cutoff and the latter is ineffective to repeat to its output circuit the signal applied to its input circuit. At the same time, however, this value of control potential causes the control electrode 19 of the vacuum tube 18' of switching stage 13' to become so positive that a continuous current flows between this control electrode and the cathode associated therewith, with the result that the signal applied to the input circuit terminals 27, 28 of the switching stage 13' produces a signal voltage of substantially the same amplitude across the resistor 61 of the stage and only a negligibly small portion of the signal voltage is applied to the control electrode 19 of the vacuum tube 18' of the stage. The switching stage 13' is therefore, for all practical purposes, ineffective to translate its signal to its output circuit.

When the control potential has a larger value at which the switching stage 15' is effective to translate its signal from its input circuit terminals 27, 28 to its output circuit terminals 29, 30, the signal voltages developed across the resistors 61 of the switching stages 13' and 14', in the manner previously described in connection with the switching stage 13', prevent the switching stages 13' and 14' from being effective to translate the signals individually applied thereto. It will thus be seen that the switching stages of this arrangement are only responsive to individual amplitude values of the control potential selectively to translate the signals individually applied thereto from the input circuit to the output circuit associated therewith.

The Fig. 6 modification of the invention is essentially similar to that of Fig. 5, similar circuit elements being designated by similar reference numerals, except that a pair of rectifier devices 63, 64 replaces each of the vacuum tubes 18' of the Fig. 5 arrangement. In the present arrangement, the input circuit terminal 22 of the electronic switch 10'' is directly connected through the series resistors 60' and 61' of each stage 13'', 14'' and 15'' to the output circuit terminal 29 thereof. The rectifier devices 63, 64 are connected with opposite polarities, that is, with the anode of one rectifier device connected to the cathode of the other rectifier device, and are included in a series circuit between the junction of the resistors 60', 61' and ground, this series circuit including the biasing battery 25.

A small biasing source comprising a battery 65 of approximately 1.5 volts potential is connected in series between the rectifier device 63 and the battery 25 and has a polarity to bias the anode of the rectifier device 63 negative with respect to its cathode for a purpose presently to be considered. A similar biasing source compris-

ing a battery 66 is similarly connected between the rectifier device 64 and the battery 25.

Considering now the operation of the Fig. 6 modification of the invention, assume that the control potential applied to the input circuit terminals 22, 23 of the electronic switch 10" has a given small potential, for example zero potential. The battery 25 under the conditions assumed, causes the rectifier device 63 of each of these switching stages 13", 14", and 15" to be conductive, the current flowing from the battery 25 through the circuit external to the control circuit terminals 22, 23, or through resistance R, the resistor 60', and the rectifier device 63. The rectifier device 63 of each switching stage has relatively low conductance under such conditions and the signal applied to the input circuit terminals 27, 28 of each such stage is thus caused to traverse the conductive rectifier device 63 and, consequently, is not applied to the output circuit terminals 29, 30 of each stage.

Now assume that the control potential applied to control circuit terminals 22, 23 has a higher value than that of the battery 25 of any of the electronic switching stages. The control potential under these conditions causes the rectifier device 64 of each stage to become conductive, the rectifier device 63 being rendered nonconductive. The signal applied to the input circuit terminals 27, 28 of each of the switching stages is thus again caused to traverse the conductive rectifier device 64 and, consequently, is not applied to the output circuit terminals 29, 30 of such stage. However, when the value of the control potential is just equal to that of the battery 25 of any of the switching stages 13", 14" or 15", neither of the rectifier devices 63 or 64 of that stage is rendered conductive by the control potential and the battery 25. Under this condition, the batteries 65 and 66 cause the rectifier devices 63 and 64 to be nonconductive over a small range of approximately 1.5 volts, whereby neither device is rendered conductive by the small amplitude signal applied to the input circuit terminals 27, 28 of that stage. Consequently, this applied signal is repeated to its output circuit terminals 29, 30. The resistors 60' in this arrangement are used as isolating resistors to prevent the application of a signal of one of the switching stages, when that stage is translating the signal to its output circuit, from being applied to the output circuit terminals 29, 30 of the other stages of the electronic switch.

From the above description of the several modifications of the invention, it will be evident that there is applied to the vacuum tube or tubes of each switching stage an alternating signal potential and a unidirectional step-control potential. Since these two potentials are applied in series to the switching-stage vacuum tube or tubes, it will be seen that the alternating signal potential is superimposed upon each step of the control potential, whereby the same effect is produced as though the amplitude of the alternating signal potential varied only over predetermined amplitude ranges. Consequently, the transformers 24, 26 and the control circuit comprising control circuit terminals 22, 23 comprise means for applying to each of the stages a signal input having an effective amplitude varying over a predetermined amplitude range, at least a portion of each of the signal input circuits being common to all of the stages. The batteries 25, the sources of screen potential +Sc, the sources of anode potential +B, and the load resistors 31 comprise

means individual to the stages for controlling the conductance characteristic of each stage thereof to render each of the stages only responsive to individual amplitude ranges of the signal input selectively to translate the portion of the signal input lying within said amplitude ranges.

Also from the above description of the invention, it will be seen that a very versatile electronic switch is provided and one which is capable of adaptation to many applications. The electronic switch of the invention possesses the advantages of substantially instantaneous operation, accurate and positive control of the selective-switching operation, and provides an arrangement whereby one or more signals may be selectively or simultaneously translated as desired to one or more output circuits of the electronic switch. There is the further advantage that the electronic switch of the invention is relatively simple and inexpensive and may be built into a relatively small and compact unit.

The term "conductance characteristic" as used in the claims appended hereto is intended to denote the transconductance of the switching stages where this factor is predominantly important, as in the Figs. 1 and 5 arrangements, or the conductance of the vacuum-tube switching stages where the latter is predominantly important, as in the Fig. 6 arrangement.

While there have been described what are at present considered to be the preferred embodiments of this invention, it will be obvious to those skilled in the art that various changes and modifications may be made therein without departing from the invention, and it is, therefore, aimed in the appended claims to cover all such changes and modifications as fall within the true spirit and scope of the invention.

What is claimed is:

1. An electronic switch comprising, a plurality of vacuum-tube switching stages each including an output circuit at which a signal translated by the stage is developed, the conductance characteristics of said stages depending primarily on the values of space currents of said vacuum tubes, a signal input circuit for each of said stages, means for applying to each of said stages a signal input having an effective amplitude varying over a predetermined amplitude range, at least a portion of each of said signal input circuits being common to all of said stages, and means individual to said stages for controlling the conductance characteristic of each stage thereof to render each of said stages responsive to individual portions of said amplitude range of said signal input, selectively to translate the portions of said signal input lying within said portions of said amplitude range, said last-named means in at least one of said stages including means for rendering said one of said stages unresponsive to all amplitude values of said input signal different from the said portion of said amplitude range individual to said one of said stages.

2. An electronic switch comprising, a plurality of vacuum-tube switching stages each including an output circuit at which a signal translated by the stage is developed, the transconductances of said stages depending primarily on changes of the space currents of said vacuum tubes, a signal input circuit for each of said stages, means for applying to each of said stages a signal input having an effective amplitude varying over a predetermined amplitude range, at least a portion of each of said signal input circuits being common to all of said stages, and means individual to said

13

stages for controlling the transconductance characteristic of each stage thereof to render each of said stages responsive to individual portions of said amplitude range of said signal input, selectively to translate the portions of said signal input lying within said portions of said amplitude range, said last-named means in at least one of said stages including means for rendering said one of said stages unresponsive to all amplitude values of said input signal different from the said portion of said amplitude range individual to said one of said stages.

3. An electronic switch comprising, a plurality of vacuum-tube switching stages each including at least one vacuum tube having a control electrode, a screen electrode and an anode, an output circuit for each of said stages including a load impedance coupled to the anode of the vacuum tube thereof and adapted to have developed thereacross a signal translated by said each stage, a signal input circuit for each of said stages, means for applying to each of said stages a signal input having an effective amplitude varying over a predetermined amplitude range, at least a portion of each of said signal input circuits being common to all of said stages, means for biasing each of said screen electrodes and each of said control electrodes to predetermined operating biases, the values of said operating biases and the values of said load impedances being proportioned to render each of said stages responsive only to individual portions of said amplitude range of said signal input, selectively to translate the portions of said signal input lying within said portions of said amplitude range.

4. An electronic switch comprising, a plurality of vacuum-tube switching stages each including an input circuit having a circuit portion adapted to have applied thereto a signal and each including an output circuit at which said signal is developed after translation through said each stage, the conductance characteristics of said stages depending primarily on the values of space currents of said vacuum tubes, another circuit portion of said input circuit being common to all of said stages and being adapted to have applied thereto a control potential having selectively-variable amplitude values, and means individual to said stages for controlling the conductance characteristic of each thereof to render each of said stages responsive to at least individual amplitude values of said control potential, selectively to translate said applied signals from the input circuit to the output circuit associated therewith, said last-named means in at least one of said stages including means for rendering said one of said stages unresponsive to all amplitude values of said control potential different from the said amplitude value individual to said one of said stages.

5. An electronic switch comprising, a plurality of vacuum-tube switching stages each including an input circuit having a circuit portion adapted to have applied thereto a signal and each including an output circuit at which said signal is developed after translation through said each stage, the conductance characteristics of said stages depending primarily on the values of space currents of said vacuum tubes, another circuit portion of said input circuit being common to all of said stages and being adapted to have applied thereto a control potential having selectively-variable amplitude ranges, and means individual to said stages for controlling the conductance characteristic of each thereof to render each of said stages

14

responsive to one individual amplitude range of said control potential, selectively to translate said applied signal from the input circuit to the output circuit associated therewith, said last-named means in at least one of said stages including means for rendering said one of said stages unresponsive to all amplitude values of said control potential different from the said amplitude range individual to said one of said stages.

6. An electronic switch comprising, a plurality of vacuum-tube switching stages each including an input circuit having a circuit portion adapted to have applied thereto a signal and each including an output circuit at which said signal is developed after translation through said each stage, the conductance characteristics of said stages depending primarily on the values of space currents of said vacuum tubes, another circuit portion of said input circuits being common to all of said stages and being adapted to have applied thereto a control potential having selectively-variable amplitude values, and means for individually fixedly biasing each of said stages to control the conductance characteristic thereof to render each of said stages responsive to at least individual amplitude values of said control potential, selectively to translate said applied signals from the input circuit to the output circuit associated therewith, said last-named means in at least one of said stages including means for rendering said one of said stages unresponsive to all amplitude values of said control potential different from the said amplitude value individual to said one of said stages.

7. An electronic switch comprising, a plurality of vacuum-tube switching stages each including an input circuit having a circuit portion adapted to have applied thereto a signal and each including an output circuit at which said signal is developed after translation through said each stage, the transconductances of said stages depending primarily on changes of the space currents of said vacuum tubes, another circuit portion of said input circuits being common to all of said stages and being adapted to have applied thereto a control potential having selectively-variable amplitude values, means individual to said stages for imparting to each of said stages a relatively high transconductance when said control potential has an individual amplitude value and relatively low transconductance for other amplitude values thereof to render each of said stages responsive only to an individual amplitude value of said control potential, selectively to translate said applied signals from the input circuit to the output circuit associated therewith.

8. An electronic switch comprising, a plurality of switching stages each including at least one vacuum tube having a control electrode and an input circuit coupled thereto, each of said input circuits having one portion individual to the switching stage associated therewith and adapted to have applied thereto a signal and another portion common to all of said switching stages and adapted to have applied thereto a control potential having selectively-variable amplitude values, an output circuit for each of said stages at which the signal individual to said each stage is developed after translation therethrough, and means individual to said stages for rendering each of said stages responsive to at least individual amplitude values of said control potential, selectively to translate said applied signals from the input circuit to the output circuit associated therewith, said last-named means in at least one

of said stages including means for rendering said one of said stages unresponsive to all amplitude values of said control potential different from the said amplitude value individual to said one of said stages.

9. An electronic switch comprising, a plurality of vacuum-tube switching stages each including an input circuit having a circuit portion adapted to have applied thereto a signal and each including an output circuit at which said signal is developed after translation through said each stage, the conductance characteristics of said stages depending primarily on the values of space currents of said vacuum tubes, another circuit portion of said input circuits being common to all of said stages and being adapted to have applied thereto a control potential having selectively-variable amplitude values, a source of operating bias included in each of the individual circuit portions of said input circuit, the values of said operating biases being proportioned to render each of said stages responsive to at least individual amplitude values of said control potential, selectively to translate said applied signal from the input circuit to the output circuit associated therewith, and the values of said operating biases in at least one of said stages being further proportioned to render said one of said stages unresponsive to all amplitude values of said control potential different from the said amplitude value individual to said one of said stages.

10. An electronic switch comprising, a plurality of switching stages each including at least one vacuum tube having a control electrode and an anode, an input circuit coupled to each of said control electrodes and having a circuit portion individual to said stages, each of said individual circuit portions being adapted to have applied thereto a signal, an output circuit including a load impedance coupled to each of said anodes and adapted to have said signal developed thereacross after translation through said each stage, the conductance characteristics of said stages depending primarily on the values of space currents of said vacuum tubes, another circuit portion of said input circuits being common to all of said control electrodes and being adapted to have applied thereto a control potential having selectively-variable amplitude values, and means included in each of the individual circuit portions of said input circuit for biasing said control electrodes to a predetermined operating bias, the values of the operating biases and the values of said load impedances being proportioned to render each of said stages responsive to at least individual amplitude values of said control potential, selectively to translate said applied signals from the input circuit to the output circuit associated therewith, said last-named means in at least one of said stages including means for rendering said one of said stages unresponsive to all amplitude values of said control potential different from the said amplitude value individual to said one of said stages.

11. An electronic switch comprising, a plurality of switching stages each including at least one vacuum tube having a control electrode, a screen electrode and an anode, an input circuit coupled to each of said control electrodes and having a circuit portion individual to said stages, said individual circuit portions being each adapted to have applied thereto a signal, an output circuit including a load impedance coupled to each of said anodes and adapted to have said signal de-

veloped thereacross after translation through said each stage, means for biasing each of said screen electrodes to a predetermined operating bias, means included in each of the individual circuit portions of said input circuit for biasing said control electrodes to predetermined operating biases, another circuit portion of said input circuits being common to all of said stages and being adapted to have applied thereto a control potential having selectively-variable amplitude values, the values of the operating biases and the values of said load impedances being proportioned to render each of said stages responsive to at least individual amplitude values of said control potential, selectively to translate said applied signal from the input circuit to the output circuit associated therewith.

12. An electronic switch comprising, a plurality of vacuum-tube switching stages each including an input circuit having a circuit portion common to all of said stages and a circuit portion individual to said each stage and adapted to have applied thereto a signal, an output circuit for each of said stages at which the signal individual to said each stage is developed after translation therethrough, the conductance characteristics of said stages depending primarily on the values of space currents of said vacuum tubes, means for generating and applying to said common circuit portion of said input circuits a control potential the amplitude values of which increase by successive steps, and means individual to said stages for controlling the conductance characteristic of each thereof to render each of said stages responsive to at least individual amplitude values of said control potential, selectively and successively to translate said applied signals from the input circuit to the output circuit associated therewith, said last-named means in at least one of said stages including means for rendering said one of said stages unresponsive to all amplitude values of said control potential different from the said amplitude value individual to said one of said stages.

13. An electronic switch comprising, a plurality of vacuum-tube switching stages each including an input circuit having a circuit portion common to all of said stages and a circuit portion individual to said each stage and adapted to have applied thereto a signal, an output circuit for each of said stages at which the signal individual to said each stage is developed after translation therethrough, the conductance characteristics of said stages depending primarily on the values of space currents of said vacuum tubes, means for generating and applying to said common circuit portion of said input circuit a periodic control potential the amplitude values of which increase during a recurrent period thereof by successive steps, and means individual to said stages for controlling the conductance characteristic of each thereof to render each of said stages responsive to at least individual amplitude values of said control potential, selectively and successively during recurrent periods to translate said applied signals from the input circuit to the output circuit associated therewith, said last-named means in at least one of said stages including means for rendering said one of said stages unresponsive to all amplitude values of said control potential different from the said amplitude value individual to said one of said stages.
